UNITED STATES PATENT OFFICE

120,133

DESIGN FOR A COMBINED FENDER AND SKIRT GUARD

John R. Morgan, Oak Park, Ill., assignor to Sears, Roebuck and Co., Chicago, Ill., a corporation of New York

Application September 14, 1939, Serial No. 87,216

Term of patent 14 years

To all whom it may concern:

Be it known that I, John R. Morgan, a citizen of the Republic of Guatemala, residing at Oak Park, in the county of Cook and State of Illinois, have invented a new, original, and ornamental Design for a Combined Fender and Skirt Guard, of which the following is a specification, reference being had to the accompanying drawing, forming a part thereof.

Fig. 1 is a side elevation of a combined fender and skirt guard embodying my new design.

Fig. 2 is a plan view of the same.

Fig. 3 is a front elevation of the same.

Fig. 4 is a rear elevation of the same.

Both sides of the device appear alike.

I claim:

The ornamental design for a combined fender and skirt guard, substantially as shown and described.

JOHN R. MORGAN.
